UNITED STATES PATENT OFFICE

2,445,321

GOVERNOR

William T. Fox, Jr., United States Navy

Application November 29, 1945, Serial No. 631,764

1 Claim. (CL. 123—103)

(Granted under the act of March 3, 1883, as amended April 30, 1928; 370 O. G. 757)

1

My invention relates to governors for controlling supply of fuel to internal combustion engine, particularly Diesel engines, to maintain a desired speed despite fluctuations of load.

In accordance with my invention, the use of a centrifugal governor, directly or through a hydraulic servo-system, to control the fuel is dispensed with and in lieu thereof there is provided a biased piston, or equivalent, whose position is determined by the rate of flow of a liquid, preferably the engine fuel, delivered at a rate varying as a function of the engine speed.

Further in accordance with my invention, the speed may be held constant at any magnitude within a substantial range by provision of a variable orifice in the discharge line from the chamber in which the piston, or equivalent, is movable.

My invention further resides in the features of construction, combination and arrangement hereinafter described and claimed.

For an understanding of my invention and for illustration of an embodiment thereof, reference is made to the accompanying drawing in which:

Fig. 1 schematically illustrates a speed-control system.

Fig. 2 partly in section, illustrates the governor and pump shown in Fig. 1.

Fig. 3 is an end view of the pump shown in Fig. 2.

Fig. 4 is a sectional view taken on line 4—4 of Fig. 2.

Fig. 5 is a detail view of valve structure shown in Figs. 2 and 4.

Fig. 6 is a sectional view taken on line 6—6 of Fig. 5.

Fig. 7 is a plan view of the governor shown in Fig. 2.

Fig. 8 is a plan view of the governor-cylinder shown in Fig. 2.

Internal combustion engines of the Diesel type require, and of the gasoline type are often provided with, fuel control governors to maintain a substantially constant speed despite fluctuations in load. For smaller engines where the force required to move the injector racks, or equivalent fuel valve structure, is small and the permissible cost is low, a centrifugal governor with its flyweights directly supplying the valve-actuating power or injector rack-actuating power is most commonly used.

When a centrifugal governor is so used directly to actuate the fuel valve or valves, it has several inherent disadvantages: it must be large and cumbersome to derive sufficient power from the flyweights and it has inferior regulating char-

acteristic which further deteriorates with wear of the parts.

For larger engines, the movement of the flyballs of a centrifugal governor is utilized to operate the pilot valve of a servo-system including a hydraulic motor for adjusting the fuel valve. This so-called hydraulic governor is an expensive precision apparatus requiring skilled maintenance and repair service.

10 In both of these types of governors, the flyball frame is driven from the engine which involves considerable mechanical complication or expensive engineering in providing for transmission of rotary motion from the engine to the flyballs and 15 of valve-actuating motion from the flyballs to the fuel-valve structure.

The governor hereinafter described has none of the above disadvantages: it is inexpensive to manufacture, simple to adjust and repair, and 20 may be located at any desired location without introduction of difficulties or complications in transmission of motion.

25 Referring to Fig. 1 and Fig. 2, the governor comprises a cylinder 1 having inlet port 2 and outlet port 3 adjacent one end thereof. The piston 4 is biased by spring 5, whose opposite ends engage the piston 4 and cylinder head 6 respectively, toward the ported end of the cylinder and in its extreme position, as shown in Fig. 30 2, leaves a chamber 7 through which passes the discharge of a pump 8 driven by engine 9.

35 Essentially the governor consists of a spring loaded piston opposing the delivery of liquid by the pump 8. With a fixed outlet 3 from cylinder 1, the position of the piston is determined by the volume of liquid delivered in unit time; the liquid in seeking escape through orifice 3 builds up pressure in chamber 7 and effects movement of piston 4 until balance exists between the pressure exerted by the spring and the pressure of the fluid. 40 The higher the engine speed, the greater the rate of delivery of liquid to chamber 7 and the further piston 4 is forced to the left, Fig. 2, against the expansive force of the spring; conversely, as the engine speed falls, the fluid pressure falls and 45 the piston is moved to the right by the spring until balance is restored.

The motion of the piston is transmitted externally of cylinder 1 by piston rod 10 which 50 passes through a guide formed in cylinder head 6. As by suitable linkage 11, motion of the piston is transmitted to the injector rack, or other valve structure, for reducing the delivery of fuel as the engine speed increases and for increasing the delivery of fuel as the engine speed decreases.

Consequently, the governor serves to maintain the engine speed constant despite fluctuations of load upon the engine.

In the case of Diesel engines, the liquid utilized for speed control of the engine may be the engine fuel itself and pump 8 may be the usual fuel pump of the positive displacement, vane or rotary type pump, with which all such engines are provided. As shown in Fig. 2, the governor may be attached directly to the pump 8 or it may be located wherever convenient to accommodate or simplify mechanical linkage to the fuel valves and the necessary flow connections provided by lines 12, 13 and 14.

As thus far described, the governor has only one speed setting determined by the fixed orifice 3. To provide for constancy of any selected speed variable at will of the operator, a manually adjustable valve 15 is introduced in the discharge line 14 of the governor. Preferably, as shown in Fig. 2, this speed-setting valve is attached to or forms part of the governor 1.

The casing 16 of this valve is provided with a port 17 which overlies a slot 25 at the end of a channel, Figs. 2 and 8, in the upper face of governor cylinder 1 and extending from the discharge port 3. The rotatable valve member 18, Figs. 2, 4, 5 and 6, is provided with a wedge-shaped opening 19 which cooperates with port 17 variably to restrict discharge from the governor in accordance with the angular position of member 18.

The port or opening 19 extends to the central passage 20 extending axially of member 18 and in flow communication through openings 21 with the circumferential groove 22 which is in line with outlet port 23 in casing 16.

When handle 24 is moved to position for which the triangular slot 19 coincides with the matching port 17, there is a minimum restriction to discharge and consequently minimum back pressure is developed within chamber 7. Accordingly, the piston 4 moves inwardly to the position corresponding with maximum rate of fuel injection. As handle 24 is moved in reverse direction to positions closer and closer to the "off" position, the slot 19 more and more restricts the flow through port 17 and the increased pressure in chamber 7 forces the piston 4 to left causing the fuel valve V successively to assume positions corresponding with the lower and lower speed settings of handle 24. Slot 19 is preferably wedge shaped to afford more flexible operation at light loads.

After the engine has been stopped, leakage allows the piston 4 to move inwardly to full throttle position in readiness for re-starting. When flow of fuel is completely restricted by misalignment of ports 17 and 19, as in the case of shutting down the engine, the usual spring-loaded by-pass valve in the pump 8 prevents excessive pressure rise while the engine is coasting to a full stop.

It is pointed out that in system shown in Fig. 1, all fuel to the injectors first passes through the governor thus avoiding possibility of inoperative-

ness of the governor, for lack of its operating medium, while fuel is being supplied to the engine. In brief, as long as fuel is supplied for operation of the engine it is effective for control of speed of the engine and moreover the rate at which fuel is supplied to the injectors is not affected by the fact that same medium is used for operation of the governor.

The governor has an inherently drooping characteristic which affords the stability essential to practically all uses of prime movers.

While I have disclosed an embodiment of my invention for purpose of illustration, it is to be understood it is not limited thereto but is coextensive in scope with the appended claim.

The invention described herein may be manufactured and used by or for the Government of the United States of America for governmental purposes without the payment of any royalties thereon or therefor.

For brevity in the appended claim, the term fuel valve is used generically to include injector control rod or rack, metering mechanism, fuel pump rack and equivalent devices for controlling the admission of fuel to an internal combustion engine.

What I claim is:

A speed-governor for an internal-combustion engine comprising a cylinder having inlet and outlet ports adjacent one end thereof for flow connection respectively with the fuel pump and fuel valve of the engine, a piston movable in said cylinder, a manually adjustable valve for variably restricting the flow through said outlet port, a piston movable in said cylinder, spring means biasing said piston to position adjacent said one end of the cylinder, and structure for transmission of movement of said piston to said fuel valve said manually adjustable valve including a cylindrical valve chamber in the discharge line, a valve sleeve within said cylindrical valve chamber, an inlet port in the valve chamber, said cylinder outlet port being connected to said valve chamber inlet port, a V-shaped port in said valve sleeve adapted to be rotated into and out of coincidence with said valve chamber inlet port, and a throttle handle for rotating said valve sleeve.
